UNITED STATES PATENT OFFICE.

ELIZABETH M. LIMERICK, OF WATSONVILLE, CALIFORNIA.

STOCKING-DRYING DEVICE.

1,290,257.

Specification of Letters Patent.

Patented Jan. 7, 1919.

Application filed February 27, 1918. Serial No. 219,418.

To all whom it may concern:

Be it known that I, ELIZABETH M. LIMERICK, a citizen of the United States, residing at Watsonville, in the county of Santa Cruz and State of California, have invented certain new and useful Improvements in Stocking-Drying Devices; and I do hereby declare the following to be a full, clear, and exact description of the invention, such as 10 will enable others skilled in the art to which it appertains to make and use the same.

My invention relates to improvements in a device whereby a plurality of stockings, socks or the like may be supported and attached to a clothes line in such a manner as 15 to permit them to be efficiently dried.

A further object of this invention is to provide a stocking supporting device which is capable of holding a plurality of pairs 20 of stockings, socks or the like in such a manner as to obviate the tearing thereof due to attachment to the line.

Another object of this invention is to provide a stocking drying device which includes 25 a supporting member upon which a plurality of pairs of stockings or the like may be arranged and having a plurality of clasps adapted to removably secure the stocking supporting device to a clothes line, thus occupying a comparatively small space.

A further object of this invention is to provide a stocking supporting device of this character, which will be simple, practical and comparatively inexpensive in construction 35 and one that can be manufactured and sold at a low cost.

With these and other objects in view, the invention consists in the novel combination and arrangement of parts hereinafter more 40 fully described and set forth in the claims hereto appended.

In the drawing:

Figure 1 is a front elevation of my improved stocking drying device illustrating 45 the same assembled and attached to a supporting line.

Fig. 2 is a vertical transverse sectional view taken on the line 2—2 of Fig. 1.

Fig. 3 is a vertical transverse sectional 50 view taken on the line 3—3 of Fig. 1.

Fig. 4 is a top plan view illustrating the device attached to the supporting line in a different manner.

Like numerals of reference designate 55 corresponding parts in all the figures of the drawing.

Referring to the drawing, the numeral 5 indicates a stocking supporter in its entirety which is constructed of a single length of material such as wire or the like. The member is coiled intermediate its ends as at 6 to provide the lower supporting bar 7 and the upper attaching bar 8. The free end of the attaching bar is bent to provide a keeper 9 which is adapted to receive the supporting 60 bar to retain the latter therein after the stockings have been arranged upon the said bar. The terminal of the supporting bar terminates into an insertion point 10 to facilitate the ready insertion of the said bar 65 through suitable loops sewed to the stockings, socks or the like so as to render it easy to place the stockings, socks or the like upon this bar to render them capable of being 70 quickly dried and to also avoid tearing or otherwise injuring the stockings or the like 75 when applying them to the supporting device.

A plurality of substantially U-shaped supporting clamps are provided and are 80 adapted to be slidably secured to the attaching bar 8. The U-shaped clasps 11 have pivotally connected in their webs by one end the shanks 12 and the free ends of these shanks terminate into the eyes 13 which slidably receive the upper attaching bar 8. The arms of the U-shaped members curve 85 inwardly as at 13 and outwardly as at 14 to provide the rope engaging portions. The terminals of the rope engaging portions are 90 curved outwardly as at 15 to provide guides whereby said clasps may be easily snapped upon a supporting line, designated A in the drawing, to support the supporting member 95 5 in such a position as to permit the stockings or the like carried by the bar 7 to be quickly and efficiently dried.

It will be understood that by virtue of the pivotal connection of the member 12 with the webs of the U-shaped clasps that 100 the member 5 may be turned at any angle with relation thereto, thus providing means whereby the same may be supported in a comparatively small space.

One of the clasp members has pivotally 105 secured to its web and depending therefrom a hook 14, this hook constituting a brace, and is adapted to have its free end removably secured to the supporting bar to retain the same against relative lateral movement.

In use, the member 10 is released from

the keeper 9 and the stockings or the like have sewed thereto suitable loops which loops are arranged over the bar 7 and the bar 7 replaced in the keeper 9 and by virtue of the clasps the device is fastened to the supporting line A and the stockings are quickly and readily dried.

Having thus described my invention what I claim is:

10. 1. A drying device of the class described including a supporting member, a plurality of clasps slidably mounted upon said supporting member, and a brace pivotally secured to one of said clasps and adapted to 15 be removably attached to the supporting member to retain the same against tilting or lateral displacement.
2. A drying device including a supporting member having an upper attaching bar 20 and a lower supporting bar, means for re-

movably securing the supporting bar to the attaching bar, a plurality of U-shaped clasps, pivoted loops secured to the webs of the clasps and slidably arranged upon the attaching bar of the supporting member, said clasps facilitating means whereby the supporting member may be removably attached to a line, and a pivoted brace hook carried by one of the eyes of one clasp and adapted to engage the supporting rod 30 of the supporting member to retain the same against tilting or displacement with relation thereto.

25 In testimony whereof I affix my signature in presence of two witnesses.

ELIZABETH M. LIMERICK.
